DRYING APPARATUS

Hans Koch, Hamburg-Rahlstedt, and Hans Forster, Hamburg-Bergedorf, Germany, assignors to Kurt Korber & Co. K. G., Hamburg-Bergedorf, Germany

Application March 7, 1956, Serial No. 570,120

Claims priority, application Germany March 14, 1955

6 Claims. (Cl. 34—208)

This invention relates generally to drying apparatus and more particularly to a conveyor type of drying apparatus arranged to transport and dry elongated smoking articles such as cigarettes.

Drying apparatuses of the type utilizing frames or trays to hold the cigarettes are well known. Usually the trays are of such depth as to accommodate the length of a cigarette. The cigarettes are loaded end-wise into the trays, which may be screened on one side to help hold the cigarettes. In one type of prior art arrangement the loaded trays were introduced at one side of the drying chamber and removed from the other. The drying was accomplished by forcing warm air through the trays from a high pressure area therebeneath to a lower pressure area thereabove. During the drying operation the loading and unloading doors were closed. The operator after loading the drying chamber through the loading door then had to move rapidly to the other side to the unloading door to remove the trays with the dried cigarettes.

An improvement in this arrangement involved a rotating table in the drying chamber which permitted loading and unloading on the same side of the apparatus. Here again warm air was forced through the cigarette laden trays from bottom to top.

Arrangements such as this when used in cigarette production lines involved alternate machine groups arranged one after the other, each machine group comprising the cigarette machine, the drying apparatus and the packing machine. Usually the arrangement of the machines lacks uniformity and is difficult to interlock and control. As a consequence it was usually preferred to locate the cigarette machines, the drying apparatus and the packing machines in separate rooms.

One object of this invention is to provide a cigarette drying apparatus which eliminates the aforesaid problems.

Another object of this invention is to provide a cigarette drying apparatus adaptable for location at any site in the production system for convenient loading and unloading.

Specifically it is an object of this invention to provide a cigarette drying apparatus involving a conveyor means which may be used to convey cigarettes in trays from the cigarette machine through the drying apparatus to the packing machine, or, alternatively, which involves a self contained conveyor and drying chamber which may be conveniently located along the production path.

The foregoing statements are merely illustrative of the various aims and objects of this invention. Other objects and advantages will become apparent from a study of the following disclosure when considered in conjunction with the accompanying drawings in which:

Fig. 1 is a front view of the drying apparatus with the housing partly removed showing the drying chamber and the conveyor therewithin.

Fig. 2 is a schematic plan view of the apparatus, and

Fig. 3 is an enlarged sectional view taken on the line III—III of Fig. 1.

In Fig. 1 the trays 1 loaded with cigarettes are carried

2

in racks 2 suspended beneath an endless conveyor 3. The conveyor 3 moves in a clockwise manner as seen in Fig. 2 and indicated by arrows 5 entering drying chamber 6 through a loading port 8 and leaving the drying chamber 5 through an unloading port 9. The conveyor belt 10 moves about respective conveyor sprockets 11 and 12, one or both of which may be driven by suitable motors (not shown). Racks 2 comprise upper and lower rack sections 2a and 2b each of which is adapted to receive 10 a tray 1, as seen in Figs. 1 and 3.

The drying chamber 6 is supported upon a suitably fabricated base 14 beneath which a centrifugal blower 15 of conventional construction is situated. The drying chamber is fabricated of any suitable sheet material comprising sheet material sides 16, floor 17 and top 18, providing a closed chamber having inlet ports 20 and outlet ports 21 in the floor thereof communicating with inlet and outlet blower ducts 22 and 23, respectively. An endless belt 25 having openings 26 therein indexed with the 15 individual racks 2 rotates about drums 27 and 28 within drying chamber 6 between the rows of racks 2. This is best seen in Figs. 2 and 3. This belt is synchronized with the conveyor either through mechanical connection with the conveyor (not shown) or by its own motor drive (not 20 shown). A belt support generally designated 30 is disposed between the vertical sides of belt 25 and comprises lower guides 31 at floor level and upper guides 32 supported by spaced vertical sheets 33 and joined across the top by a sheet 34.

30 The arrangement described defines an outer inlet pressure chamber 36 and an inner lower pressure chamber 37 respectively communicating with inlet ports 22 and outlet ports 23 to complete the warm air circuit. Thus a pressure differential is maintained across the drying trays from 35 the outer chamber 36 to the inner chamber 37, the air path extending endwise of the cigarettes through the trays 1 and through the openings 26 in belt 25 into the inner chamber 37. The warm air circuit is completed through outlet duct 23, blower 15 and inlet duct 22. By means of 40 baffles (not shown), the use and application of which is well known to those skilled in the art, the warm air flow can be controlled and directed. To insure efficient air passage through the cigarette trays the individual racks 45 2 may be provided with flat rear faces which seat against belt 25 about respective openings 26 to form a reasonably satisfactory air seal. A better seal is obtainable by facing the rear edges of the trays with sponge rubber or other pliable material which seats against the belt and seals the rear tray edges about the openings 26 in belt 25.

With this arrangement the cigarettes are subjected to warm drying air twice during passage through the drying chamber; first while moving from the loading port 8 to the end of the chamber, and second, while moving from the end of the chamber to the unloading port. The trays 55 of dried cigarettes are removed from the racks 2 externally of the chamber 6 at station 38 where they may be transported in any suitable manner to the packing machine storage area.

At the beginning of the operation some of the racks 2 60 may be covered by plates such as shown at 2c in Fig. 1. Thus as the dryer racks are loaded the plates serve to block unlimited air flow across the empty racks in the drying chamber. Naturally suitable controls must be provided to control conveyor and belt speed in synchronization so that proper time is provided in transit through the drying chamber to achieve proper drying. Again such controls being conventional are not shown in the interest of simplicity. After proper synchronizing and indexing of the conveyor and the belt 25, if such is necessary as a result of lack of mechanical interlocking, the synchronized drive will be brought to the desired operating speed.

70 It will now be appreciated that an integrated dryer ap-

paratus is herein provided which affords a high degree of flexibility in adapting it to various production line organizations. With the arrangement shown it is necessary to provide separate transporting means to the loading station 39 and from the unloading station 38. In some instances this may be undesirable in which case conveyor 3 may be more extensive than shown, completing an endless circuit from the cigarette machine output point through the dryer apparatus to the input point of the packing machine. To simplify the problem the trays 1 may be loaded in the racks 2 and unloaded therefrom manually.

Although but one embodiment of this invention has been herein illustrated and described it will be appreciated by those skilled in the art that this invention is susceptible of modification both in its details and in the organization of such details without departing from the spirit and scope of the principles hereof. Accordingly, it is intended that the foregoing disclosure and the showings made in the drawings shall be considered only as illustrative of the principles of this invention and not construed in a limiting sense.

The invention is claimed as follows:

1. Drying apparatus for smoking articles such as cigarettes, comprising a drying chamber, a conveyor moving through said chamber, individual racks on said conveyor having upper and lower sections, trays arranged endwise in said upper and lower sections of said racks, an endless belt in said drying chamber synchronized with said conveyor and having openings therein indexed with said individual racks so that air flow through said racks passes through said openings, and means for circulating warm air through said trays and opening in said chamber.

2. Drying apparatus for smoking articles such as cigarettes, comprising a drying chamber, a conveyor moving through said chamber, individual racks on said conveyor having upper and lower sections, trays arranged endwise in said upper and lower sections of said racks, an endless belt in said drying chamber synchronized with said conveyor and having openings therein indexed with said individual racks so air flow through said racks passes through said openings, rollers intermediate the ends of said chamber guiding movement of said belt, said belt defining an inner chamber within said drying chamber, blower means having an outlet pressure duct connected to said drying chamber outside of said belt and having an inlet lower pressure duct connected to said inner chamber.

3. Apparatus as set forth in claim 1 wherein said conveyor comprises a reversing sprocket in one end of said drying chamber wherein said racks pass in reversed directions along opposite sides of said belt being subjected twice to drying air flow during movement through said chamber.

4. Apparatus as set forth in claim 2 wherein said conveyor comprises a reversing sprocket in one end of said drying chamber wherein said racks pass in reversed directions along opposite sides of said belt being subjected twice to drying air flow during movement through said chamber.

5. Drying apparatus for smoking articles such as cigarettes, comprising a drying chamber, a conveyor moving through said chamber, individual racks on said conveyor having upper and lower sections, trays arranged endwise in said upper and lower sections of said racks, an endless belt in said drying chamber synchronized with said conveyor and having openings therein indexed with said individual racks so that air flow through said racks passes through said openings, each drying rack having sealing edges thereof adjacent to and contacting said belt about said openings to seal air flow at said edges.

6. Drying apparatus for smoking articles such as cigarettes, comprising a drying chamber, a conveyor moving through said chamber, individual racks on said conveyor having upper and lower sections, trays arranged endwise in said upper and lower sections of said racks, an endless belt in said drying chamber synchronized with said conveyor and having openings therein indexed with said individual racks so that air flow through said racks passes through said openings, each drying rack having sealing edges thereof adjacent to and contacting said belt about said openings to seal air flow at said edges, rollers intermediate the ends of said chamber guiding movement of said belt, said belt defining an inner chamber within said drying chamber, blower means having an outlet pressure duct connected to said drying chamber outside of said belt and having an inlet lower pressure duct connected to said inner chamber.
